(57) **CLAIM**

I claim the ornamental design for the detachable firearm camera, as shown and described.

DESCRIPTION

FIG. 1 illustrates an isometric perspective view of a detachable firearm camera showing my design;
FIG. 2 is a forward perspective view thereof;
FIG. 3 is a left perspective view thereof;
FIG. 4 is a right perspective view thereof;
FIG. 5 is a rear perspective view thereof;
FIG. 6 is a top perspective view thereof;
FIG. 7 is a lower perspective view thereof; and,
FIG. 8 is a lower perspective view thereof.
